JOHANN F. M. PATITZ, OF MILWAUKEE, WISCONSIN, ASSIGNOR, BY MESNE ASSIGNMENTS, TO ALLIS-CHALMERS MANUFACTURING COMPANY, A CORPORATION OF DELAWARE.

REGULATOR.

1,095,667.

Specification of Letters Patent.

Patented May 5, 1914.

Application filed May 3, 1909. Serial No. 493,648.

To all whom it may concern:

Be it known that I, JOHANN F. M. PATITZ, a citizen of the United States, residing at Milwaukee, in the county of Milwaukee and State of Wisconsin, have invented a certain new and useful Improvement in Regulators, of which the following is a specification.

This invention relates to improvements in the construction of regulators and particularly in that class known as spring regulators.

The object of the invention is to produce a regulator which is very sensitive in its operation thereby giving closer regulation than has heretofore been attained. To attain this result in regulators it is necessary to have the parts balanced, this being one of the features of the present invention.

20 A clear conception of the invention can be obtained by reference to the accompanying drawings in which like reference characters designate the same parts.

Figure 1 is a front view, partly in section, 25 of a regulator built according to the invention. Fig. 2 is an end view of the device shown in Fig. 1.

The casings 1, which serve as the weights and also partially inclose the spring 2, are 30 concentrically supported upon the levers 6, 7, by means of the pins 9. These pins 9 have their axes in the horizontal plane of the axis of the spring 2. The ends of the spring 2 have the supports 3 fixed thereto, 35 these supports 3 being minutely adjustable to various positions along the spring 2 to vary the stiffness of the spring. The adjusting bolts 4, which pass through the ends of the casings 1 and are fixed thereto by 40 the lock nuts 5, are screwed into the supports 3. This means provides for the adjustment of the supports 3 as to their distance from casing 1 and hence gives a second adjustment for the ends of the spring 45 2, within the casings 1, by turning the bolts 4 thus varying the initial spring stress.

The weights of casings 1 are mounted directly and indirectly independently of each other as to mutual guiding, that is, there is 50 no sliding or guiding of the weights, the one upon the other as in the telescoping casings of the prior art, and this independent mounting also avoids any mutual sliding of parts connected to or extended from the 55 weights or casings. The weights or casings

1 are not guided by any means other than the levers 6, 7, thus reducing the friction to a minimum.

The corresponding levers 6, 7, are parallel to each other and are connected to the pins 8 which are pivotally mounted in the bracket 10. The bracket 10 is fixed to the regulator drive shaft 14, which shaft 14 is connected in any suitable manner, not shown, to the main shaft of the engine. This drive shaft 14 has fixed thereto the spline 15 which allows the horizontal movement of the sleeve 16 along the shaft 14, at the same time transmitting rotary motion from the shaft 14 to the sleeve 16.

The lever 11 has one end fastened to the shaft 8 to which the lever 7 is connected. The other end of this lever 11 is provided with the pin 12 which forms a pivotal connection between the lever 11 and the link 13. The lower end of the link 13 is pivoted to the sleeve 16 by the pin 17.

The collar 18 is mounted upon the sleeve 16, this collar 18 being rotatable upon the sleeve 16, but being prevented from lateral shifting thereon by the nut 21. The collar 18 has two guide pins 22 which allow its axial movement relative to the guide 23. This guide 23 is fixed to the upper part of the supporting stand 24 of the regulator.

The link 20 which is pivoted to the collar 18 at its upper end by the pin 19, is connected at its lower end to the lever 27 by a pin 26. The lever 27, having the hub 28, is supported upon the shaft 30, which shaft 30 is supported in the bracket 25. The lever 29 is also attached to the hub 28, so that any movement of the lever 27 will be transmitted to the lever 29 through the hub 28. The valve gear to be regulated is suitably connected to this lever 29, this connection being well known in the art.

In the operation of the regulator the rotary motion of the engine is transmitted to the regulator drive shaft 14. This causes the rotation of the sleeve 16 and, through the levers 6, 7, the upper portion of the regulator. The centrifugal force exerted upon the casings 1 will cause a tension within the spring 2. The forces exerted by the casings 1 will be balanced since only one spring 2 is used. The casings 1 will move outward parallel to the spring 2, due to the arrangement of the levers 6, 7. This outward movement of the weights or casings 1 parallel to

the spring 2 constitutes motion of translation of the weights not considering rotation, and the weights during such movement have their centers of gravity constantly lying in the axis of the spring.

5 Any motion of the casings 1 will be transmitted through the levers 7, 11, and the link 13 to the sleeve 16. This sleeve 16 will move the collar 18 which will in turn move the links 20 which will act upon the levers 27, 10 29, and hence upon the valve gear to be operated.

15 If it is desired to change the speed, the spring 2 may be adjusted by means of the bolts. The sensitiveness is changed by turning the supports 3, thus lengthening or shortening the spring 2 by making effective a greater or fewer number of coils. It can be seen that with this arrangement the action of the forces directly in line with the 20 axis of the spring 2, and the double adjustment of said spring 2, makes the governor more universally applicable. The use of one spring maintains a balancing of the 25 forces exerted by the casings 1.

It should be understood that it is not desired to be limited to the exact details of construction shown and described, for obvious modifications will occur to a person 30 skilled in the art.

It is claimed and desired to secure by Letters Patent:

1. In a regulator, a spring having an axis, 35 weights directly and indirectly independent of each other as to mutual guiding each connected to an end of said spring and having their centers of gravity constantly lying in the axis of said spring, a rotary element, and means on said element for supporting said 40 weights to have motion of translation not considering rotation.

2. In a regulator, a spring having an axis, 45 weights directly and indirectly independent of each other as to mutual guiding surrounding said spring and each connected to an end thereof and having their centers of gravity constantly lying in the axis of said spring, a rotary element, and means on said element for supporting said weights to have 50 motion of translation not considering rotation.

3. In a regulator, a single helical spring 55 having an axis, weights directly and indirectly independent of each other as to mutual guiding each connected to an end of said spring and having their centers of gravity constantly lying in the axis of said spring, a rotary element, and means on said element for supporting said weights to have 60 motion of translation not considering rotation.

4. In a regulator, two opposing weights 65 directly and indirectly independent of each other as to mutual guiding, means for mounting each of said weights so as to adapt

the same for motion of translation not considering their rotation with the regulator, and a single spring the ends of which are respectively connected to said weights.

5. In a regulator, two opposing weight members directly and indirectly independent of each other as to mutual guiding, a spring having an axis, said weight members having their centers of gravity constantly lying in the axis of said spring, a 70 support member adjustably connected to each end of said spring, and at each end of said spring a bolt lying in the axis of said spring and adjustable in one of said members and rotatable in the other of said members.

6. In a regulator, two opposing weight members directly and indirectly independent of each other as to mutual guiding, a spring having an axis, said weight members having their centers of gravity constantly lying in the axis of said spring, a support member adjustably connected to each end of said spring, and at each end of said spring a bolt lying in the axis of said spring and 85 directly connecting said members, said bolts being adjustable in one of said members and rotatable in the other of said members.

7. In a regulator, two opposing weights directly and indirectly independent of each other as to mutual guiding, a spring, a support connected to each end of said spring said support being adjustable along the length of said spring to adjust the stiffness thereof, and bolts each directly connecting one of said supports to one of said weights, the connection being adjustable to vary the distance between said support and said weight.

8. In a regulator, the combination of a single elastic member, a weight connected to each end of said member, a shaft having its axis transverse to the line of extension of said member, means supported from said shaft for constraining said weights to motion of translation in planes through the axis of said shaft and constituting the sole means for communicating rotation from said shaft to said weight and elastic member, and constituting the sole means with which either of said weights coacts for guiding same, and means for communicating said motion of translation to a part to be controlled.

9. In a regulator, two opposing weights 120 directly and indirectly independent of each other as to mutual guiding, means for revolving said weights about an axis, a single elastic member the ends of which are respectively connected to said weights, and connecting means between said weights and said elastic member eliminating friction during operation of the regulator.

10. In a regulator, two opposing weights 130 directly and indirectly independent of each

other as to mutual guiding, means for revolving said weights about an axis, a single tension spring the ends of which are respectively connected to said weights, and connecting means between said weights and said spring eliminating friction during operation of the regulator.

11. In a regulator, an elastic member having an axis, weights directly and indirectly independent of each other as to mutual guiding each connected to an end of said elastic member, connecting means between said weights and said elastic member for preventing transverse movement of said weights relative to the axis of said elastic member, a rotary element, and means on said element for supporting said weights to have motion of translation not considering rotation.

12. In a regulator, a helical spring having an axis, a weight connected to each end of said spring, connecting means between said weights and said spring for preventing transverse movement of said weights relative to the axis of said spring, said weights being directly and indirectly independent of each other as to mutual guiding, a rotary element, and means on said element for supporting said weights to have motion of translation not considering rotation.

13. In a regulator, a helical tension spring having an axis, weights independent of each other each connected to an end of said spring, connecting means between said weights and said spring for preventing transverse movement of said weights relative to the axis of said spring, a rotary element, and means on said element for supporting said weights to have motion of translation not considering rotation.

14. In a regulator, an elastic member having an axis, weights directly or indirectly independent of each other as to mutual

guiding each connected to an end of said elastic member and having their centers of gravity constantly lying in the axis of said elastic member, a rotary element, and means on said element for supporting said weights to have motion of translation not considering rotation.

15. In a regulator, a tension spring having an axis, weights directly and indirectly independent of each other as to mutual guiding each connected to an end of said spring and having their centers of gravity constantly lying in the axis of said spring, a rotary element, and means on said element for supporting said weights to have motion of translation not considering rotation.

16. In a regulator, an elastic member having an axis, weights directly and indirectly independent of each other as to mutual guiding surrounding said elastic member and each connected to an end thereof, said weights having their centers of gravity constantly lying in the axis of said elastic member, a rotary element, and means on said element for supporting said weights to have motion of translation not considering rotation, said motion having a component along the axis of said elastic member.

17. In a regulator, two opposing weights directly and indirectly independent of each other as to mutual guiding, means for revolving said weights about an axis, means for mounting each of said weights so as to adapt the same for motion of translation not considering the revolution, and a single elastic member the ends of which are respectively connected to said weights.

In testimony whereof, I affix my signature in the presence of two witnesses.
